UNITED STATES PATENT OFFICE.

WILLIAM F. CLASS, ALBERT J. WEATHERHEAD, AND GEORGE COLLINS, OF CLEVELAND, OHIO; SAID CLASS ASSIGNOR, BY MESNE ASSIGNMENTS, TO JACOB J. MAYER, OF SAME PLACE.

FORCE AND DRAIN FAUCET.

SPECIFICATION forming part of Letters Patent No. 328,877, dated October 20, 1885.

Application filed June 23, 1884. Serial No. 135,682. (No model.)

To all whom it may concern:

Be it known that we, WILLIAM F. CLASS, ALBERT J. WEATHERHEAD, and GEORGE COLLINS, citizens of the United States, residing at Cleveland, in the county of Cuyahoga, in the State of Ohio, have invented a new and useful Improvement in Beer Apparatus, of which the following is a specification, reference being had to the accompanying drawing, 10 forming a part thereof.

This invention relates to beer apparatus for drawing beer from the keg at a cold temperature, and for forcing air into the keg in order to maintain sufficient pressure therein to cause 15 the beer to readily flow therefrom.

A beer-drawing apparatus has heretofore been employed in which the beer keg or barrel is placed within a refrigerating-chamber and provided with an elongated spigot driven into 20 the barrel and extending through an opening in the wall of the refrigerator. In that case much difficulty was encountered in placing the barrel in such position that the spigot could be readily applied through the opening referred to in the wall of the refrigerator, and in keeping it in proper position relative to 25 said opening. Furthermore, said opening was necessarily considerably larger than the spigot, and consequently cold air would escape through said opening around said spigot, causing a rise of temperature in the refrigerator and a waste of ice. In that case an air-pump was attached to the side of the refrigerator, slightly removed from the wall thereof, 30 said wall being further provided with an opening through which the piston-rod of said pump extended, and here also cold air from the interior of the refrigerator was permitted to pass between said wall and the front end of the pump-cylinder and escape through said last-mentioned opening around the piston-rod, 35 involving a further waste of ice.

The object of this invention is to avoid the difficulties above mentioned, and to provide an 40 apparatus in which the beer may be kept at a cold temperature without waste of the cooling agent, and in which the kegs or barrels can be placed at any convenient point with-

in the refrigerator, constituting a part of this apparatus.

The drawing is a vertical longitudinal section of this improved beer apparatus.

This apparatus comprises a refrigerator, A, in which the beer barrel or keg B containing the beer to be operated upon is placed; a faucet 55 fixed to the wall of the refrigerator, an air-pump also fixed to said wall, and flexible pipes for connecting said faucet and air-forcing apparatus with said barrel. The refrigerating-compartment may be of any suitable construction. A faucet, C, is fixed to the wall A of said refrigerator, its tube passing through said wall. A flexible pipe, D, is connected at one end to the inner end of said faucet-tube and provided at the other end with a tubular 60 plug, E, having a lateral branch, e, and provided with a cock, c', adapted for insertion in the spigot-hole of the beer-barrel. This plug is provided at its inner end with a short flexible draft-tube, d, the inner end of which rests 65 on the bottom of the barrel. The valve of the faucet C is preferably of the kind known as the "globe" valve and turns on a horizontal axis. An air-pump, F, is fixed to the wall of the refrigerator at the interior thereof adjacent to said faucet, the cylinder of said pump being parallel with the faucet-tube. The wall of the refrigerator is provided with a slot, a, which extends transversely through said wall in line with the axis of the pump-cylinder, being elongated radially to the tube of the faucet C. The outer end of the pump-cylinder is sealed against said wall and surrounds said slot, whereby escape of air from the interior of the refrigerator through said slot is effectively prevented. The inner end of the pump-cylinder F is closed by a head, k. This head is provided with perforated ears k' beyond the periphery of the cylinder, and with an ejection-port, k''. Screw-bolts f extend 80 from the exterior of the refrigerator through an outer metallic plate, e, on the outer face thereof, through the wall thereof, and within the interior of the refrigerator, parallel with the pump-cylinder, their inner ends being 85 screw-threaded and passed through said ears 90

k' of the cylinder-head *k*. Clamping-nuts *k*³ are screwed onto said rods against the ears of said head, whereby the outer end of the pump-cylinder is tightly pressed against the inner face of the wall of the refrigerator and supported in contact therewith. A flexible pipe, *N*, is connected at one end to the eduction-port of the pump and provided at its opposite end with a tubular plug, *s*, adapted to fit the bung-hole of the barrel or other opening therein.

The apparatus is provided with an induction air-valve, *m*, which in this case is shown as located on the piston *M* of the pump, and the apparatus is also provided with a suitable check-valve, *p*, which is preferably located in the plug *s*. A lever, *L*, is pivoted to the faucet *C*, and may be connected with the valve of the faucet, as shown, so as to actuate said valve when oscillated sufficiently to accomplish that result. A connecting-rod, *l*, is hinged at its inner end to the piston of the air-pump, and at its outer end said rod is hinged to the lever *l*, passing through the slot *a* in the wall of the refrigerator. When the lever *L* is actuated, the rod *l* reciprocates longitudinally in the slot *a*, and also plays vertically or laterally therein, and performs the double function of piston and connecting rods. When the lever *L* is connected with the valve of the faucet and is moved through the entire arc of its stroke, the valve of the faucet *C* is actuated for the drawing of beer from the barrel.

We are aware that a faucet and air-pump provided with flexible pipes have heretofore been attached to an ordinary counter or table; but in that case the pump is exposed to the ordinary temperature, and warm air is forced into the beer.

The construction, combination, and arrangement of parts herein described constitute a simple, convenient, and compact apparatus for drawing beer from its keg in a cool state.

We claim as our invention—

1. The combination of a refrigerator, a faucet whose tube is fixed in and extends through the wall of said refrigerator, said wall being provided with a slot adjacent to said faucet-tube, and an air-pump whose piston-rod extends through said slot, the cylinder of said pump having one end closely fixed against said wall over and around said slot, and a lever pivoted to said faucet outside said wall, substantially as described.

2. The combination of a refrigerator, a faucet whose tube is fixed in and extends through

the wall of said refrigerator, said wall being provided with a slot adjacent to said faucet-tube, an air-pump whose piston-rod extends through said slot, the cylinder of said pump having one end closely fixed against said wall over and around said slot, a lever pivoted to said faucet outside said wall, a flexible pipe connected at one end with the eduction-port of said pump for conducting air therefrom to a keg or barrel within said refrigerator, and a flexible pipe connected at one end to said faucet for conducting thereto beer or other liquid from said keg, substantially as described.

3. The combination of a refrigerator, a faucet whose tube is fixed in and extends through the wall of said refrigerator, said wall being provided with a slot adjacent to said faucet-tube, and an air-pump whose piston-rod extends through said slot, the cylinder of said pump having one end closely fixed against said wall over and around said slot, a lever pivoted to said faucet outside said wall, a flexible pipe connected at one end with the eduction-port of said pump and provided at the other end with a tubular plug adapted to fit the bung or other hole in a keg or barrel within said refrigerator, and a flexible pipe connected at one end with the said fixed faucet and provided at the other end with a tubular plug or faucet adapted to fit the spigot-hole of said keg or barrel, substantially as described.

4. The combination of a refrigerator, a faucet the tube of which is fixed in and extends through the wall of said refrigerator, said wall being provided with a slot adjacent to said faucet-tube, an air-pump the cylinder of which is within the refrigerator, a lever pivoted to said faucet outside said wall, and a rod connected at one end to said lever and at the other with the piston of said pump, said rod passing through said slot and being adapted to reciprocate longitudinally and play laterally in respect to its axis within said slot, substantially as described.
